(57) **CLAIM**

The ornamental design for a door facing, as shown and described.

DESCRIPTION

FIG. 1 is a front perspective view of our design;

FIG. 2 is a front elevational view;

FIG. 3 is a rear elevational view;

FIG. 4 is a top plan view;

FIG. 5 is a bottom plan view;

FIG. 6 is a cross sectional view taken along the line 6-6 of FIG. 2;

FIG. 7 is a cross-sectional view taken along the line 7-7 of FIG. 2;

FIG. 8 is an enlarged fragmentary cross-sectional view of a portion of FIG. 7;

FIG. 9 is a right side elevational view;

FIG. 10 is a left side elevational view;

FIG. 11 is a cross sectional view taken along the line 11-11 of FIG. 2;

FIG. 12 is a front perspective view of a second version of our design;

FIG. 13 is a front elevational view;

FIG. 14 is a rear elevational view;

FIG. 15 is a top plan view;

FIG. 16 is a bottom plan view;

FIG. 17 is a cross sectional view taken along the line 17-17 of FIG. 13;

FIG. 18 is a cross sectional view taken along the line 18-18 of FIG. 13;

FIG. 19 is an enlarged fragmentary cross sectional view of a portion of FIG. 18;

FIG. 20 is a right side elevational view;

FIG. 21 is a left side elevational view; and,

FIG. 22 is a cross sectional view taken along the line 22-22 of FIG. 13.

The profiles of FIGS. 8 and 19 extend continuously about all panels of the associated door facings.
